UNITED STATES PATENT OFFICE

173,294

BIRDHOUSE

Victor W. Voeks, Fredonia, Wis.

Application February 26, 1954, Serial No. 29,237

Term of patent 14 years

(Cl. D31—2)

To all whom it may concern:

Be it known that I, Victor W. Voeks, a citizen of the United States, residing at Fredonia, in the county of Ozaukee and State of Wisconsin, have invented a new, original, and ornamental Design for a Birdhouse, of which the following is a specification, reference being had to the accompanying drawings, forming a part thereof.

The dominant feature of my design resides in the full line portion of the drawing.

I claim:

The ornamental design for a birdhouse, as shown and described.
